International Search Report and Written Opinion received in PCT Application No. PCT/US2020/028542 dated Sep. 7, 2020 in 19 pages.

Primary Examiner — Nathan M Johnston

(74) *Attorney, Agent, or Firm* — Knobbe, Martens, Olson & Bear, LLP

(57) **CLAIM**

The ornamental design for a holder for a patient monitor, as shown and described.

DESCRIPTION

FIG. 1 is a perspective view of a holder for a patient monitor showing our new design;

FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof;

FIG. 8 is a rear view thereof; and,

FIG. 9 is another perspective view thereof.

Broken lines, where shown, are used to illustrate portions of the holder for a patient monitor or environmental subject matter that form no part of the claimed design.

1 Claim, 5 Drawing Sheets
